UNITED STATES PATENT OFFICE.

ELIAS T. GOLDBERG AND AARON GALBORD, OF BRIDGEPORT, CONNECTICUT.

MACHINE FOR FORMING RINGS.

1,187,141.

Specification of Letters Patent. Patented June 13, 1916.

Application filed November 13, 1915. Serial No. 61,358.

To all whom it may concern:

Be it known that we, ELIAS T. GOLDBERG, a citizen of the United States of America, and AARON GALBORD, a subject of the Czar of Russia, both residing at Bridgeport, Fairfield county, Connecticut, have invented certain new and useful Improvements in Machines for Forming Rings, of which the following is a full, clear, and exact description 10 of the invention, such as will enable others skilled in the art to which it appertains to make and use the same.

Our invention relates to machines for forming rings preparatory to the operation 15 of soldering and polishing them, and consists of certain details of construction and combination of parts hereinafter fully described and then particularly pointed out in the claims that conclude this description.

20 In the accompanying drawings Figure 1 is a front elevation of our machine—Fig. 2 a plan view—Fig. 3 a section at the line x , x , of Fig. 2—Fig. 4 a section at the line y , y , of Fig. 2, and Fig. 5 a detail perspective of the 25 anvil.

Similar numerals of reference denote like parts in the several figures of the drawing.

1 is the bed of the machine and 2 a block 30 rising therefrom. This block has a vertically disposed opening or recess 3 within which is a reciprocatory head 4 having on its rear side face a rack 5. Extending through the rear of this block from side to side is a circular opening or recess 6 which 35 is disposed at right angles to the recess 3, and journaled within this recess 6 is a rock shaft 7 that is prevented from displacement in any suitable manner, as, for instance, by a pin 8 driven through the block 2 into an 40 annular groove 9 around said shaft. To the outer end of this rock shaft is secured any suitable hand lever 10 for operating the shaft, and the opposite end of the shaft is formed into a pinion 11 which is in mesh 45 with the rack 5.

12 is a hammer bar whose rear end is secured within the head 4 by a screw 13 and extends within vertical guideways 14 in opposite sides of the block 2. The forward 50 portion of this bar projects beyond the block 2 and is formed into differential circular portions 15, 16, 17.

18 is an anvil detachably secured within the bed 1 and having differential circular recesses 19, 20, 21, which are immediately be-

low the portions 15, 16, 17, and correspond therewith in contour.

The operation of our improvement is as follows:—A ring with a segment cut therefrom, in accordance with our invention set 60 forth in our pending application Serial No. 61,357 filed on even date herewith, is placed around one of the portions 15, 16, 17, and the hand lever 10 operated to hammer the ring into a complete circlet with the severed ends abutting, the ring meanwhile being shifted around the circular portion by hand 65 until the desired result is obtained. Of course it will be understood that the bar and anvil 18 may be replaced by other similar 70 parts whose circular portions and recesses correspond with the size of the ring to be treated. By the continued hammering action of the bar 12 with the frequent shifting of the ring, the latter will be perfectly 75 formed and in condition for soldering and polishing.

In utilizing our device for making a ring from a straight blank, the length of the latter is, of course, predetermined by the 80 size of ring desired, and the ends of the blank are sheared at the proper angle so that they will closely abut in the completed ring. By the constant hammering action of the bar 12 a straight blank is gradually 85 curved into the form of a ring, it being understood that the curved portions of the bar and the corresponding curved recesses in the anvil are suitable for the size of ring to be formed. 90

The anvil is secured within a suitable way in the bed 1 by screws 22 driven through the edge of the bed against the anvil, and when a different anvil is to be used the 95 screws are backed so that the anvils may be changed.

We claim:—

1. A machine of the character described comprising a block having a recess therein and coinciding guideways provided in opposing walls of the block recess, a hammer head slidable in the block recess, a hammer bar secured to the head and projecting therefrom into the guideways of the block, an anvil with which the hammer bar co-operates, and means for actuating the hammer head. 100

2. A machine of the character described comprising a block having a recess therein and coinciding guideways provided in op- 110

2
posing walls of the block recess, a hammer head slideable in the block recess and provided with an opening therethrough, a hammer bar passing through the head opening and into the block guideways, one projecting end of the hammer bar being formed into differential circular portions, an anvil having corresponding differential recesses to receive the portions of the hammer bar, and 10 means to reciprocate the hammer head.

3. In a machine of the character described, a body having a block provided with a recess, a hammer head slideable in the block recess and formed with a rack part, said 15 block having a second recess communicating with the first recess, a rock shaft journaled in the block and having a toothed part in the second recess of the block meshing with the rack part of the head, an anvil, and a

hammer bar carried by the head for coöperation with the anvil.

4. A machine of the character described comprising a movably mounted hammer head, a hammer bar adjustably carried by the head and provided with circular differential portions, and an anvil for the bar having differential recesses corresponding with said hammer bar portions, said hammer bar being adjustable to compensate for wear of its portions.

In testimony whereof we affix our signatures in presence of two witnesses.

ELIAS T. GOLDBERG.
AARON GALBORD.
